UNITED STATES PATENT OFFICE.

CHARLES F. SMITH, OF NEW BRITAIN, CONNECTICUT, ASSIGNOR TO
LANDERS, FRARY & CLARK, OF NEW BRITAIN, CONNECTICUT.

DESIGN FOR A FERRULE.

SPECIFICATION forming part of Design No. 35,663, dated February 4, 1902.

Application filed January 2, 1902. Serial No. 88,254. Term of patent 7 years.

To all whom it may concern:

Be it known that I, CHARLES F. SMITH, a citizen of the United States, residing at New Britain, in the county of Hartford and State of Connecticut, have invented and produced a new and original Design for a Ferrule, of which the following is a specification, reference being had to the accompanying drawings, forming part thereof.

Figure 1 is a side elevation of a ferrule, showing my design. Fig. 2 is a plan view of the same.

As shown in the drawings, the plain band 3 is at the handle end of the ferrule, followed by a rounded bead 4. The ferrule, which is oval in end view, is intended for use for table-cutlery. Near the middle there is another rounded bead 5 in the neck of the ferrule, which is smaller at the said bead 5 than at

either of its ends. Between the beads 4 and 5 the groundwork is plain, and on the said ground there are scroll ornaments 6 in relief at the top and bottom, and on the sides the ornaments 7 and 8, the latter overlapping the bead 4 and band 3. The flaring portion 9 between the left-hand end of the ferrule and the bead 6 is ornamented by leaflets 10, extending from the bead 6 toward the flaring end, all as shown.

Having described my invention, what I claim as new, and desire to secure by Letters Patent, is—

The design for a ferrule, as herein shown and described.

CHARLES F. SMITH.
